UNITED STATES PATENT OFFICE

ARTHUR F. O'CONNOR, OF CHICAGO, ILLINOIS, ASSIGNEE TO UNION RAILWAY EQUIPMENT COMPANY, OF CHICAGO, ILLINOIS, A CORPORATION OF ILLINOIS

ICE BUNKER FOR REFRIGERATOR CARS

Application filed September 20, 1928. Serial No. 307,114.

This invention relates to ice bunkers for refrigerator cars.

In refrigerator cars as at present constructed it is the customary practice to provide at each end of the car a bunker for the reception of ice which is discharged into the bunker through a hatch door in the roof of the car immediately above the bunker.

The bunker is constructed to provide a bulkhead which separates it from the storage space within the car, and it is customary to so arrange the bulkhead that it will afford openings above and below the bulkhead for the circulation of air toward and from the center of the car where perishable commodities are stored.

The present invention is directed not only to the construction of the bunker as a whole, but particularly to the construction of the bulkhead, the wall of which is formed of corrugated metal, which affords the necessary strength and rigidity and is free from the objections in cost of upkeep, and so forth, which have attended the use of wooden bulkheads for a like purpose.

The present construction is designed to permit the bulkheads to be manufactured at the factory and installed without difficulty into the interior of the car, and the invention relates to the general construction of the bulkhead, as well as to the various means employed for connecting the various constituent portions thereof and securing the same to the body of the car.

Further objects and details will appear from the description of the invention, in conjunction with the accompanying drawings, wherein—

Figure 1 is a cross section through the interior of a refrigerator car corresponding substantially to line 1—1 of Figure 2, and showing the bulkhead with the outer insulating facing removed.

Figure 2 is a longitudinal sectional view corresponding substantially to line 2—2 of Fig. 1, and showing the insulating facing in position with reference to the main supporting wall of the bulkhead.

Figure 3 is a sectional plan view taken substantially on the line 3—3 of Figure 1 and

also showing the bulkhead with the insulating facing in position thereon.

Figure 4 is a sectional detail showing the construction of the bunker floor to afford a grating for the deposit of ice;

Figure 5 is a sectional detail, showing the method of supporting one of the ends of the bunker floor, taken on line 5—5 of Fig. 3;

Figure 6 is a sectional detail, taken on line 6—6 of Figure 5;

Figure 7 is a sectional detail, showing the method of supporting the bunker floor at the center, taken on line 7—7 of Figure 3; and,

Figure 8 is a sectional detail of the same, taken on line 8—8 of Figure 7.

The drawings represent the end portion of a refrigerator car constructed in accordance with the customary practice, to provide an outer end wall 10, an inner end wall or sheathing 11, an outer side wall 12, an inner side wall or sheathing 13, a ceiling 14 and a floor 15. The floor supports an inner flooring 16 of slatted formation, as indicated in Figures 2 and 3.

The bunker at each end is separated from the storage space within the car by a bulkhead 17, the wall of which is of sheet metal provided with a series of outwardly bulging spaced ribs or corrugations 18 extending horizontally in parallel relation to one another and terminating in reduced end portions 19 which merge into the plane flat body of the plate composing the wall, so that the side margins, as well as the margins at top and bottom, will lie flat and within the general plane of the bulkhead.

The side edges of the metal wall are outwardly turned to provide vertically extending edge flanges 25—25 which, as shown, are each secured by bolts to the outer flange 26 of a Z-bar 27, which Z-bars on each side are secured to the inner side walls of the car. The upper edge of the metal wall is provided with an inturned flange 22 extending at right angles to the main plane of the wall to strengthen the same.

Secured to the rear of the metal wall is a plurality of spaced vertical wooden bars 20, said bars being secured to the metal wall by

rows of bolts 21, entered through the plane portions of the metal wall intermediate the corrugations. An inner or rear wall of the bulkhead is afforded by a mesh screening 24 which is secured by nailing or in any other suitable manner to the exposed inner edges of the wooden bars or slats, and this mesh wall affords the surface of contact with the ice within the bunker and serves to define 5 circulating passages between the mesh wall, and corrugated wall of the bulkhead, these passages discharging into the bottom of the car. 10

The front face of the bulkhead is provided by an insulating wall or facing 240, made up of laminations of wood with insulating material 241 disposed therebetween. The facing 240 is secured to the metal wall of the bulkhead by means of rows of bolts 242, preferably extending through said wall at the 15 peaks or crests of the corrugations. Although the facing 240 is adequately supported by the metal wall of the bulkhead, when fastened in the manner indicated, due to the fact that the side edges of the facing are slightly spaced 20 from the inclined ends of the corrugations, I preferably provide filler members 243, which may be fitted within the spaces provided by the Z-bars 27, and bolts 244 extended through the edges of the facing, the filler blocks and 25 the Z-bars, thereby providing an adequately braced bulkhead construction of great strength. 30

The floor or ice grate of the bunker is afforded by a plurality of metallic slats 28 which extend transversely of the bunker—that is, longitudinally of the car, and each metallic slat is of inverted U-shaped formation terminating at each edge in an attaching flange 29, as best shown in Figure 4. The 35 edges of the attaching flanges lie in spaced relation to one another to afford slots or openings 30 between the adjacent slats and below the ice chamber.

The forward and rear edges of the metallic slats rest upon and are supported by angle bars 31 and 32 respectively, while the slats are supported intermediately by the provision of a bridge strap 33 to which the flanges 29 are secured by rivets 34 (see Figure 4). The 40 slatted bunker floor, as a whole, is supported in elevated relation above the floor of the car by the provision of a medial bridge 35 of channel formation, as shown in Fig. 8, which bridge terminates at its forward end in a depending foot 36 which extends downwardly to a cross beam 37 to which it is secured by means of an angle clip 38.

The rear end of the bridge 35 embraces and is supported upon a shelf 39 outwardly extending from a bracket 40 secured to the end wall of the car, and the bridge is held against displacement by the provision of a dowel pin 41, which extends through the shelf 39, the bridge 35, and the flange of the angle bar 32 45 upon which the rear ends of the slats are sup-

ported and to which they are riveted, as best indicated in Fig. 8. The dowel pin 41 is provided with a slot 42 which receives a wedge-shaped locking pin 43 which serves to lock the parts together. 70

The method of supporting the angle bars 31 and 32 is best illustrated in Figs. 5 and 6, from which it will be seen that each of the side walls 13 of the car has secured thereto an angle bar 44, the horizontal flange 45 of which supports a plate 46, upon which rests the ends of the angle bars 31 and 32 which support the slats. The plate 46 is riveted to the bars 31 and 32, and constitutes an end reinforcement for the slatted metallic floor of the bunker, and each of the plates 46 is secured in place by dowel pins 47 and locking wedges 48 like those heretofore described. 75

The end walls of the bunker are afforded by mesh screening 49, and the rear wall by 80 a screening 50, which screen walls are secured to studdings 51—51 standing vertically from the inner side and end walls of the car adjacent to that portion thereof which affords the bunker space. 85

The Z-bars 27 extend upwardly above the bulkhead and afford flanges for the securement of the ends of a mesh screening 52 which serves to screen off the space above 90 the bulkhead. 95

The arrangement above described is one which provides for a bunker structure which is all metallic with the exception of the wooden bars or slats constituting a portion of the bulkhead, and thereby eliminates the objections which have been heretofore noted with respect to the use of wood in the construction of ice bunkers. 10

The method of constructing the bulkhead is one which affords ample strength and rigidity, and at the same time makes provision for the required air circulation and the necessary insulation. Ample provision is made for the down circulation of the cold air through the slatted grate or floor of the ice chamber, and the means provided for securing and supporting the grate and bulkhead enable these portions of the structure to be readily inserted or removed as occasion may require. The structure of the slatted grate affords 11 adequate provision for reinforcement at the ends and sides of the floor structure, which thus becomes a self-contained unit, and the slats themselves, being corrugated, may be formed of relatively thin gauge metal to afford sufficient strength and rigidity to prevent distortion or indentation of the metal slats. 12

By constructing the bulkhead and floor in the manner indicated, and by providing the supporting brackets and other special means required for attachment, the bunker as a whole can be readily constructed at the factory and assembled in the car by the securement of the attaching means provided. 13

Although the invention has been described with particularity, it is not the intention to limit the same except as indicated in the claims, since modification thereof can be made without departing from the spirit of the invention.

I claim:

1. In a structure of the class described, a metallic bulkhead including a corrugated body portion and marginal plane surfaces, certain edge extremities of the latter being provided with flanges extending substantially at right angles to the main plane of the bulkhead in one direction and another edge 10 extremity being provided with a flange extending in the opposite direction.

2. In a structure of the class described, a bulkhead including a corrugated metallic wall, a wall of foraminous material, means 20 for spacing said walls; and means connecting said foraminous material and spacing means to said metallic wall whereby the latter supports the former.

3. In a structure of the class described, a bulkhead including a corrugated metallic wall, an inner wall of foraminous material, and spacing means interposed between the 25 said walls, said walls and spacing means being secured together to provide a unitary structure with air circulation space between said walls.

4. In a structure of the class described, a bulkhead including a corrugated metallic wall provided with angularly turned edge 35 flanges; and angular members secured to said flanges and providing means by which the bulkhead may be secured in position.

5. In a structure of the class described, a bulkhead including a corrugated metallic wall, an inner foraminous wall spaced from 40 one side of said metallic wall and secured thereto and a wall of insulating material secured to the opposite side of said metallic wall, said bulkhead providing air circulating space between said metallic wall and said foraminous wall.

6. In a refrigerator car, the combination with the side and end walls thereof; of a bulkhead including a corrugated metallic wall secured to the side walls of the car and defining with said side and end walls an ice bunker, 50 said metallic wall being secured to said side walls; an inner wall of foraminous material spaced from said metallic walls and secured thereto, said bulkhead providing an air circulating space between said walls.

7. In a structure of the class described, a slatted floor comprising a plurality of elongated metal slats in spaced relation to one another, each slat having a central corrugation and laterally extending flanges, metallic bars to which the ends of said flanges are secured, and connecting bars to which the slat supporting bars are connected.

8. In a structure of the class described, a

slatted floor comprising a plurality of elongated metal slats of inverted U-shaped formation, in spaced relation to one another, and provided with laterally extending flanges, metallic bars to which the ends of said flanges are secured, and connecting bars to which the slat supporting bars are connected.

9. In a structure of the class described, a slatted floor comprising a plurality of corrugated metal slats in spaced relation to one another, metallic bars to which the ends of the slats are secured, connecting bars to which the slat supporting bars are connected, means for supporting the connecting bars, a bridge bar terminating at its outer end in a depending foot and positioned to afford a medial support for the slat supporting bars, and a bracket for supporting the opposite end of the bridge bar.

10. In a structure of the class described, a slatted floor comprising a plurality of corrugated metal slats of inverted U-shaped formation, in spaced relation to one another, metallic bars to which the ends of the slats are secured, connecting bars to which the slat supporting bars are connected, means for supporting the connecting bars, a bridge bar terminating at its outer end in a depending foot and positioned to afford medial support for the slat supporting bars, and a bracket for supporting the opposite end of the bridge bar.

11. In combination with a car body, an ice bunker having a floor comprised of metallic slats of corrugated formation and in spaced relation to one another, means for connecting the ends of the slats, means for supporting the slatted floor in elevated relation to the car floor, a bulkhead extending across the body of the car and in spaced relation to the top and bottom of the car, to provide for air circulation, said bulkhead comprising a metallic wall having horizontally extending corrugations; and an inner foraminous wall supported from said metallic wall in spaced relation with reference thereto to provide for air circulation between said walls.

12. In combination with a car body, an ice bunker having a floor comprised of metallic slats of corrugated formation and in spaced relation to one another, means for connecting the ends of the slats, means for supporting the slatted floor in elevated relation to the car floor, said means including an intermediate disposed bridge bar having its outer end downturned to provide a supporting foot, a bulkhead extending across the body of the car and in spaced relation to the top and bottom of the car to provide for air circulation, said bulkhead comprising a metallic wall having horizontally extending corrugations, and an inner foraminous wall supported from said corrugated wall to provide for air circulation between said walls.

13. In combination with a car body, an ice bunker having a floor comprised of metallic

- slats of corrugated formation and in spaced relation to one another, means for connecting the ends of the slats, means for supporting the slatted floor in elevated relation to the car floor, a bulkhead extending across the body of the car and in spaced relation to the top and bottom of the car to provide for air circulation, said bulkhead comprising a metallic wall having horizontally extending corrugations, and an inner foraminous metallic wall secured to said corrugated wall in spaced relation with respect thereto, the upper end of said corrugated wall being provided with an inturned flange to strengthen the same, and the edges of said corrugated wall being outwardly flanged to provide means by which it is secured in position.
14. In combination with a car body, an ice bunker having a floor comprised of metallic slats of corrugated formation and in spaced relation to one another, means for connecting the ends of the slats, means for supporting the slatted floor in elevated relation to the car floor, said means including an intermediate disposed bridge bar having its outer end downturned to provide a supporting foot, a bulkhead extending across the body of the car and in spaced relation to the top and bottom of the car to provide for air circulation, said bulkhead comprising a metallic wall having horizontally extending corrugations, vertically disposed wooden bars supported from said corrugated wall and an inner foraminous metallic wall secured to the wooden bars and defining air circulation space between said walls.
15. In a structure of the character described, the combination with a refrigerator car having side, end and bottom walls; of a bulkhead cooperating with said walls at one end of the car to define an ice bunker, said bulkhead including a metallic wall embossed within its edges and provided with angularly turned flanges; and Z-bars extending the full height of the car and secured to the walls thereof, the free flanges of said Z-bars being secured to the flanges of said bulkhead so as to support the bulkhead in position to provide air circulating spaces above and below the same.
16. In a structure of the character described, the combination with a refrigerator car having side, end, top and bottom walls; of a bulkhead cooperating with said walls at one end of the car to define an ice bunker, said bulkhead including a corrugated metallic body portion supported by the wall of said car so as to be arranged with its top and bottom edges spaced from the ceiling and floor of the car to provide for air circulation; a wall of foraminous material supported by said body portion in spaced relation with reference thereto; and a wall of insulating material secured to said body portion at the

side opposite to that to which said foraminous wall is connected.

In witness that I claim the foregoing I have hereunto subscribed my name this 12th day of September, 1928.

ARTHUR F. O'CONNOR.
